UNITED STATES PATENT OFFICE.

JEHU H. LOWNSBURY, OF PHILADELPHIA, PENNSYLVANIA, ASSIGNOR TO
H. W. BUTTERWORTH & SONS COMPANY, A CORPORATION OF PENN-
SYLVANIA.

TENTERING-MACHINE.

SPECIFICATION forming part of Letters Patent No. 745,023, dated November 24, 1903.

Application filed March 19, 1902. Serial No. 98,917. (No model.)

To all whom it may concern:

Be it known that I, JEHU H. LOWNSBURY, of the city and county of Philadelphia, State of Pennsylvania, have invented an Improvement 5 in Tentering-Machines, of which the following is a specification.

My invention has reference to tentering-machines; and it consists of improvements which are fully set forth in the following specification and shown in the accompanying drawings, which form part thereof.

The object of my invention is to provide a simple form of support and power-transmitting gearing for driving the tentering-chains and reciprocating their carriers; and my invention comprehends certain improvements in driving mechanism for tentering-machines whereby a reciprocation may be imparted to the two parallel chains of clamps or stretching devices while driving them.

In carrying out my invention I support the longitudinal frames carrying the stretching devices so that they may be reciprocated longitudinally simultaneously in opposite directions, the said motions being secured by a transverse driving-shaft pivoted in universal bearings formed in the gearing and rocked in a horizontal plane by means of power devices. The driving-shaft is connected by suitable power-transmitting devices with the cloth-stretching chains or conveyers, whereby its rotation produces a continual longitudinal travel of said conveyers or chains simultaneously with the reciprocation of the supports therefor. The universal pivot-support for the driving-shaft comprises a fixed frame across which the driving-shaft extends and relative to which it is pivoted on a vertical axis by means of a driving-gear guided in the frame and which is universally pivoted to the driving-shaft. If desired, horizontal guiding supports for the driving-shaft, preferably formed upon or attached to the pivot-support, may be employed.

My invention also comprehends minor details of construction, all of which will be better understood by reference to the accompanying drawings, in which—

Figure 1 is a front elevation of one end of a tentering-machine embodying my improvements. Fig. 2 is a plan view of same. Fig.

3 is a sectional elevation of the power-transmitting devices on a larger scale, and Fig. 4 is a cross-section of same on line 4-4.

A are the longitudinal reciprocating frames carrying the chains of cloth-clamps or other suitable conveying devices for holding the edges of the cloth to be stretched and moving it through the machine. These frames are journaled on vertical axis formed by upright pins G, horizontally journaled at g, concentric with the driving-shaft B.

The driving-shaft B is supported by bearings M, which rest upon horizontal curved guides L upon the top portions of the arms 65 of a fixed frame C. Inside the said guides L and extending around the shaft B are guides c of forked or other shape also secured to the frame C. Journalled between the guides c c is a large ring-hub I' of the gear I. The hub 70 of this gear is connected with the shaft B by a universal joint comprising a hub D, keyed to the shaft between the bearings M M and to which is pivoted by trunnions a floating ring W, said ring W being in turn pivoted to 75 the ring-hub I' by trunnions w, constituting an axis at right angles to the axis of the trunnions d. In this manner the gear I is properly connected to and supported by the shaft B, and while being caused to rotate in a vertical plane parallel to the length of the machine the shaft is free to rotate and oscillate in a horizontal plane to maintain its geared connection at E F with the reciprocating frames A A. The shaft B, being positively 80 connected to the gear I, is held against end movement through the intervention of the hub of said gear in its action upon the guides c c. The wheel I may be any toothed wheel or other well-known type of wheel for transmitting power.

J is a transverse power-shaft driven by means of a belt and pulley K or otherwise and extends transversely across the machine and is journalled at C' in the frame C. This 95 shaft is provided with a pinion i, which meshes with the spur-wheel I, connected to the driving-shaft B. A clutch j may be used to throw the pinion i into or out of connection with the power-shaft. This will provide 100 means for putting the shaft B into or out of rotary motion.

It will be seen from the construction here in set out that the hub of the driving-wheel I is free to adjust itself vertically and is wholly independent of the bearings M, which support the shaft B. The hub of the driving-wheel I has no journal bearings whatever to hold it vertically or transversely in the plane of its revolutions, and this is important because the connections between the shaft B and wheel I cause slight movements in the vertical plane of the wheel I, which would prevent its being journaled in the bearings which support the shaft B itself. The hub I' of the wheel I, being made with flat surfaces and working between the U-shaped stationary guides c, holds the wheel in lateral position while permitting it to adjust itself freely in the plane of its revolution. The U-shaped construction of the guide c permits 20 the ready dismantling of the apparatus when necessary by lifting the shaft B vertically.

The driving-shaft B is provided with a bevel-gear E on each side of its axis, secured thereto by means of a key or feather, so as to 25 permit adjustment longitudinally upon the shaft, but to positively rotate with it. The said bevel-gears E respectively mesh with horizontal bevel-gears F, secured to vertical shafts f, extending upward, journaled upon 30 the pins G and terminating in driving-wheels H for the conveyer-chains. These wheels may be of any suitable construction—such as sprocket-wheels, for example. These shafts f are concentric with the vertical pivoted supports or pins G for the longitudinal frames A, so that during the oscillation of the driving-shaft the power-transmitting connections to the conveyer-chains are constantly maintained. The longitudinal frames A are supported, as is customary, at intervals in their 35 length by suitable pivoted supports, one of which is shown. These supports consist of a transverse frame S, centrally pivoted upon a pedestal T and having adjustable supports S' connecting with the under side of the longitudinal frames by vertical pivots s. By means of a suitable hand-screw t these supports S' and their vertical pivots may be moved to or from each other to adjust the positions of the longitudinal frames relatively 40 one to the other. These supports may be made in any other suitable manner desired.

The end of the shaft B is journaled in a box movable upon a vertical axis and carried 45 in a transversely-reciprocating frame P, movable horizontally in bearings N under the action of a cam O, which works between the flanges p. The cam O is secured upon a cam-shaft R. The cam-shaft R is geared 50 with a counter-shaft r by means of speed-reducing gears R' R², and said counter-shaft is also geared to the power-shaft J by a second set of gears J' J². It will now be observed that the power-shaft J is the primary cause of rotation of the cam to impart the reciprocation of the driving-shaft B as well as the source of power for rotating the said driving-shaft. 55

The cam mechanism above specified is fully described in the United States Patent to Gadd, No. 606,780, and no claim is made to it here. 70 The particular gearing employed or means for oscillating the driving-shaft is immaterial, as any suitable means may be employed for rotating the cam as well as other means for rotating the driving-shaft—as, for instance, such 75 means as illustrated in patents to A. McLean, No. 569,763, dated October 20, 1896, E. Ainsworth, No. 569,734, dated October 20, 1896, and R. M. Hunter, No. 568,349, dated September 29, 1896, may be used. 80

It is immaterial what particular means is employed between the driving-shaft and conveyers, since various other methods of gearing for this purpose are well known—as shown, for example, in the patents above referred to. 85

The general arrangement of the tentering-machine here shown is similar to that set out in patent to Gadd, No. 606,780, and is used simply as illustrative of such a machine as 90 my invention is applicable to, and hence while I require an oscillating driving-shaft and driving-gearing substantially of the character herein set out between it and the power-shaft for rotating it I do not restrict myself 95 to any specific details with respect to the remaining portions of the machines, since my invention is, generally speaking, applicable to all types of tentering-machines.

While I prefer the construction shown, I do 100 not limit myself to the minor details thereof, as they may be modified in various ways without departing from the spirit of my invention.

What I claim as new, and desire to secure 105 by Letters Patent, is—

1. In a tentering-machine, the combination of two longitudinal carriers or conveyers for holding the cloth to be treated, a driving-shaft transversely arranged to said conveyers 110 or carriers and adapted to oscillate upon an upright axis, power-transmitting connections between said driving-shaft and the conveyers or carriers whereby the same may be moved to cause the material to travel through the 115 machine, power devices to cause said driving-shaft to reciprocate, a fixed frame having two vertical guides adjacent to the driving-shaft at a point intermediate of the conveyers or carriers, a driving-wheel surrounding said shaft and having a hub of a width just equal to the space between the vertical guides and guided by the fixed guides so as to revolve continuously in the same plane with capacity for vertical adjustment, universal jointed connections between the driving-wheel and the oscillating driving-shaft 125 whereby they revolve together irrespective of the oscillations of the driving-shaft, oscillating bearings for the driving-shaft independent of the driving-wheel, and suitable means for rotating the driving-wheel. 130

2. In a tentering-machine, the combination of two longitudinal carriers or conveyers for

holding the cloth to be treated, a driving-shaft transversely arranged to said conveyers or carriers and adapted to oscillate upon an upright axis, power-transmitting connections between said driving-shaft and the conveyers or carriers whereby the same may be moved to cause the material to travel through the machine, power devices to cause said driving-shaft to reciprocate, a fixed frame having vertical and horizontal guides adjacent to the driving-shaft at a point intermediate of the conveyers or carriers, sliding bearings movable horizontally upon said guide-frame and in which the driving-shaft is journaled and by which it is supported, a driving-wheel surrounding and supported by said shaft and guided vertically by the fixed guides so as to revolve continuously in the same plane, universal jointed connections between the driving-wheel and the oscillating driving-shaft whereby the driving-wheel is supported by the shaft and they revolve together irrespective of the oscillations of the driving-shaft, supports for the driving-shaft independent of the driving-wheel, and suitable means for rotating the driving-wheel.

3. In a tentering-machine, the combination of two longitudinal carriers or conveyers for holding the cloth to be treated, a driving-shaft transversely arranged to said conveyers or carriers and adapted to oscillate upon an upright vertical axis, power-transmitting connections between said driving-shaft and the conveyers or carriers whereby the same may be moved to cause the material to travel through the machine, power devices to cause said driving-shaft to reciprocate, a fixed frame having vertical guides adjacent to the driving-shaft at a point intermediate of the conveyers or carriers, a driving-wheel surrounding said shaft and guided in a vertical plane by the fixed guides so as to revolve continuously in the same plane with freedom of adjustment in a vertical plane, universal jointed

connections between the driving-wheel and the oscillating driving-shaft consisting of an intermediate ring hinged to the shaft on trunnions and also hinged to the driving-wheel hub on trunnions the axes of the two sets of trunnions being at right angles to each other whereby they all revolve together and adapt themselves to each other irrespective of the oscillations of the driving-shaft, and suitable means for rotating the driving-wheel.

4. In a tentering-machine, the combination of two longitudinal carriers or conveyers for holding the cloth to be treated, a driving-shaft transversely arranged to said conveyers or carriers and adapted to oscillate upon an upright axis, power-transmitting connections between said driving-shaft and the conveyers or carriers whereby the same may be moved to cause the material to travel through the machine, power devices to cause said driving-shaft to reciprocate, a fixed frame having U-shaped vertical surfaces acting as guides adjacent to the driving-shaft at a point intermediate of the conveyers, supporting horizontally-movable bearings for the driving-shaft, a driving toothed wheel surrounding said shaft independent of its bearings and guided by the fixed guides to revolve continuously in the same plane with freedom of adjustment in a vertical plane, universal connections between the driving-wheel and the oscillating driving-shaft whereby they revolve together irrespective of the oscillations of the driving-shaft, and suitable means for rotating the driving-wheel consisting of a power-shaft and pinion meshing with the driving gear-wheel.

In testimony of which invention I have hereunto set my hand.

JEHU H. LOWNSBURY.
